COMBINED WINDOW SQUEEGEE AND MOP
HOLDER OR SIMILAR ARTICLE

Peter W. De Vore, Long Island City, N. Y.

Application May 4, 1950, Serial No. 9,696

Term of patent 7 years

(Cl. D9—2)

To all whom it may concern:

Be it known that I, Peter W. De Vore, a citizen of the United States, residing at Long Island City, in the county of Queens and State of New York, have invented a new, original, and ornamental Design for a Combined Window Squeegee and Mop Holder or Similar Article, of which the following is a specification, reference being had to the accompanying drawing and description, forming part thereof.

Fig. 1 is a plan view of a combined window squeegee and mop holder or similar article, showing my new design.

Fig. 2 is a side elevational view thereof, and Fig. 3 is an end view thereof.

The dominant features of my new design are shown in solid lines in the drawing.

The dotted line showing of a mop, cloth or wet rag in Fig. 2 is for illustrative purposes only.

The handle is broken away in Figs. 1 and 2 for convenience of illustration.

I claim:

The ornamental design for a combined window squeegee and mop holder or similar article, as shown and described.

PETER W. DE VORE.
